UNITED STATES PATENT OFFICE.

OLUF E. KJESBU AND HENRY STENSON, OF STARBUCK, MINNESOTA.

EGG-TESTER.

SPECIFICATION forming part of Letters Patent No. 430,476, dated June 17, 1890.

Application filed October 30, 1889. Serial No. 328,683. (No model.)

To all whom it may concern:

Be it known that we, OLUF E. KJESBU and HENRY STENSON, citizens of the United States, residing at Starbuck, in the county of Pope 5 and State of Minnesota, have invented certain new and useful Improvements in Egg-Testers; and we do hereby declare the following to be a full, clear, and exact description of the invention, such as will enable others skilled in the art to which it appertains to make and use the same.

The invention relates to improvements in egg-testers, such as are frequently used in stores and by dealers to discover the condition 15 of eggs; and it consists in the construction and novel combination of parts hereinafter described, illustrated in the accompanying drawings, and pointed out in the claims hereto appended.

20 In the accompanying drawings, in which similar letters of reference indicate corresponding parts, Figure 1 is a perspective view of the device as a whole. Fig. 2 is a vertical section of the device from front to rear. Fig. 25 3 is a horizontal cross-section of this device. Fig. 4 is a detail of the testing-tube. Fig. 5 is a perspective view of the covering-plate from the under side and showing a modified form of construction.

30 It must be observed that the nest or series of cells for the eggs form no part of the invention and is of any ordinary construction, it being necessary, however, that the said cells have open bottoms, so that the light can 35 shine through the eggs, and that the frame containing the cells is of proper size and shape to fit in place upon the tester.

Referring to the drawings by letter, A designates the casing of the tester, having its 40 bottom a^1 open, its sides a^2 imperforate, and its front a^3 a narrow board or plate, as shown. The edges of the sides a^3 of the casing are inclined downward toward the front for a short distance, and the top of the case is covered 45 by a board or plate a^4 .

a^5 a^6 are supporting-strips secured to the inner surfaces of the inclined part of the sides a^3 parallel to the edges of said sides and at a suitable distance below said edges.

50 B is a concave reflecting-plate, preferably of sheet metal, polished on its inner concave surface, about semicircular in cross-section,

and secured within the casing A, its edges being secured to the sides and its lowest point near the back of said casing.

55

When the device is in use, the frame C, containing the nest of cells that holds the eggs, (which frame must have a bottom removable or not and perforated below the lower ends of the cells c ,) fits into the space 60 between the sides of the casing, its lower side edges resting upon the inclined supporting-strips a^5 . The lower end of the reflecting-plate is not covered, but retains the concave shape of the section of said plate.

65

E is a covering shade-plate convex upwardly, semicircular in cross-section, having its ends filled in by the semicircular plates e , and provided centrally on top with the opening e' . The inner surface of the plate E is colored a dull black by any suitable substance.

7c

F is a testing-tube, which is designed to be used by placing one end to the eye of the operator and the lower beveled end on the egg to be tested. In use it may be passed through 75 the opening e' and have its inner end f , which is suitably beveled, placed upon the top of the egg contained in any cell c , so that the light passing up through the eggs in other cells will be shaded from the eye of the operator.

80

It is evident that when the frame C is in place and the covering shade-plate E placed on top of said frame, upon which it is snugly fitted, no light from the lamp or other burner 85 G placed in front of plate B can pass out of the casing A, and that the light which is given out from the lamp on the reflecting-plate B immediately behind it will be reflected by the plate B through the eggs in the cells 90 c , so that the operator can examine the eggs collectively through said opening e' of the covering-plate in the usual well-known manner, or by means of the tube F can examine any egg separately in the manner indicated.

95

When the tester is not in use, the covering shade-plate is placed within and the top opening covered by a flat board.

The opening a^6 in the top of the case will allow any smoke from the lamp or burner to 100 escape from the case.

Having now described our invention, we claim—

1. In an egg-tester, the combination, with

the casing, open at its bottom, having imperforate sides, its edges inclining downward to the front of the casing, which front is covered by a board or plate, and the inclined 5 supporting-strips secured to the inner surfaces of the said sides of the casing parallel to and sufficiently below its inclined edges, of the concave reflecting-plate secured within the casing and having open ends, and the covering shade-plate fitted upon the cell-frame resting on the supporting-strips, having its 10 ends closed, colored a dull dark on its inner concave surface, and provided with a central opening in its top, substantially as specified.

15 2. In an egg-tester, the combination, with

the casing A, open at the bottom, the inclined and imperforate side plates, and the supporting-strips a^5 , secured to said sides, of the concave reflecting-plate B, secured within the casing, the shade-plate E, having closed ends 20 and colored dark on its inner concave side and provided with the central opening e' in its top, substantially as specified.

In testimony whereof we affix our signatures in presence of two witnesses.

OLUF E. KJESBU.
HENRY STENSON.
